UNITED STATES PATENT OFFICE.

JAMES P. MCKINNEY, OF PITTSBURGH, PENNSYLVANIA.

HINGE

1,076,689.

Specification of Letters Patent.

Patented Oct. 28, 1913.

Application filed October 4, 1910. Serial No. 585,314.

To all whom it may concern:

Be it known that I, JAMES P. MCKINNEY, a resident of Pittsburgh, in the county of Allegheny and State of Pennsylvania, have 5 invented a new and useful Improvement in Hinges; and I do hereby declare the following to be a full, clear, and exact description thereof.

My invention relates to hinges, its object 10 being to provide a butt-hinge in which the wear is reduced to a minimum and at the same time the creaking of the hinge is eliminated, thereby giving a noiseless and easy moving hinge.

15 My invention consists in butt-hinge washers interposed between the knuckles in direct contact therewith, said washers being formed of phosphor-bronze or equivalent.

In the accompanying drawing Figure 1 is 20 a perspective view of my improved hinge; Fig. 2 is a vertical section through the joint of the hinge and Fig. 3 is a view of one of the washers removed.

In the drawing the numeral 2 designates 25 a suitable butt-hinge composed of the leaves 3 and 4. These leaves are provided with the knuckles 5 and 6 through which the pivot-pin 7 passes in the ordinary manner. The screw 9 engages the threaded seat in the 30 lowermost knuckle of the leaf 3 in the

ordinary manner. The hinge may be formed of different metals but preferably of steel, and inserted between the knuckles are the washers 10. These washers are formed of phosphor-bronze which is very hard and will 35 reduce the wear to a minimum, and at the same time such metal has a peculiar property which acts in the nature of a lubricant to reduce the friction. When the washers are interposed between the knuckles the 40 hinge works easily with slight friction and the consequent wear is reduced to a minimum. At the same time by the use of the phosphor-bronze the creaking of the hinge is avoided and without the use of a lubricant 45 the metal itself acts in the nature of a lubricant and a noiseless and easily moving hinge is provided.

What I claim is:

A butt-hinge having washers interposed 50 between the knuckles and in direct contact therewith, said washers being formed of phosphor-bronze.

In testimony whereof, I the said JAMES P. MCKINNEY have hereunto set my hand.

JAMES P. MCKINNEY.
